UNITED STATES PATENT OFFICE.

REVELET A. HALLETT, OF HARVEY, ILLINOIS.

REFLECTING HEADLIGHT.

Application filed January 8, 1922. Serial No. 526,480.

To all whom it may concern:

Be it known that I, REVELET A. HALLETT, a citizen of the United States, residing at Harvey, in the county of Cook and State of Illinois, have invented a certain new and useful Improvement in Reflecting Headlights, of which the following is a full, clear, concise, and exact description.

My invention relates to reflecting head-lights employing parabolic reflectors and has for its object an improvement in head-light construction whereby the emanating rays will be confined to selected levels. Headlights constructed in accordance with my invention are of particular use upon automobiles as the light emanating therefrom may be so directed as to avoid head-light glare upon occupants of other automobiles.

In practicing my invention I employ a reflector having a parabolic reflecting surface, a lighting center positioned to direct rays of light upon said reflecting surface, and two additional downwardly and forwardly inclined reflectors upon opposite sides of the axis of the parabolic reflecting surface.

In the preferred embodiment of the invention the lighting center is in the form of an incandescent lamp which is disposed between the two additional reflectors which themselves are preferably plane.

I will explain my invention more fully by reference to the accompanying drawing, in which Fig. 1 is a vertical sectional view showing the preferred embodiment of the invention; Fig. 2 is a sectional view, on a smaller scale, on line 2-2 of Fig. 1; Fig. 3 is a perspective view showing some of the parts of the headlight structure with other parts removed for the sake of clearness; and Fig. 4 is a side elevation of the complete lamp.

Like parts are indicated by similar characters of reference throughout the different figures.

The parabolic reflector 1 is preferably cut away so as to not extend below the parabolic axis 2, as the lower part of the parabolic reflector is not required in practicing my invention. The rear part of this reflector is formed with a circular aperture which receives the holder 3 that receives the base 4 of the incandescent lamp 5. The filament 6 of the incandescent lamp constitutes the lighting center which is at the

focus of the parabolic curve of the reflector 1. Said reflector is formed with a non-reflecting extension 4' in which there is mounted a plane mirror 7 which is located below the parabolic axis 2 and is downwardly and forwardly inclined, the incandescent lamp 5 being located in front of the reflector 7. The lamp is formed with a housing that includes a back 8 that has a circular rim 9 which receives the cylindrical portion 10 of the housing. The housing portion 10 is downwardly and forwardly inclined as indicated at 11 and terminates in a circular rim 12 that carries a gasket 13. The skirt of the circular cap ring 14 receives the circular rim 12. A light transmitting cover 15, made preferably of glass, covers the circular hole that is defined by the ring 14, light reflected from the mirror 7 passing through said cover. The housing portion 11 is substantially above the parabolic axis 2. Another plane reflector 16 rests against the housing portion 11 and is, therefore, downwardly and forwardly inclined. The plane reflector that is in front of the lighting center which slopes downwardly and forwardly having its lower and forward edge adjacent the parabolic axis, the other plane reflector that is back of the lighting center also sloping downwardly and forwardly and having its upper and rear edge also adjacent the parabolic axis. The plane mirrors 7 and 16 are nearly or substantially parallel and, being upon opposite sides of the parabolic axis and having the lighting center 6 between the same, the incident rays that pass from the lighting center to the parabolic reflector are ultimately reflected so as to pass through the light transmitting closure 15 in a predetermined direction depending upon the inclinations of the plane mirrors.

In the preferred embodiment of the invention the mirror 7 is at a larger angle to the horizontal than is the mirror 16 so that the beam of light passing through the light transmitting closure 15 will be inclined forwardly and downwardly rather than straight ahead, although the invention is not to be thus limited. The light emanating from the headlight is principally produced by the rays passing from the lighting center 6 to the parabolic reflector 1 from which these rays are reflected to the reflector 16 and are again reflected from this reflector to impinge upon the mirror 7 from

whence the rays are finally reflected to produce the desired beam of light. The rays of light which pass directly from the lighting center through the closure 15 and from the lighting center to the reflector 7 to be reflected thereby produce a soft light which is dominated by the light that is due to the rays reflected from the parabolic mirror as described.

10 While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

15 The combination with a reflector having a parabolic reflecting surface; of a lamp having a lighting center positioned to di-

rect rays of light upon said reflecting surface; a plane reflector in front of the lighting center and sloping downwardly and forwardly and having its lower and forward edge adjacent the parabolic axis; and another plane reflector back of the lighting center and also sloping downwardly and forwardly and having its upper and rear edge also adjacent the parabolic axis, the plane reflector that is in front of the lighting center being positioned to receive rays reflected from the parabolic reflector and the other plane reflector being positioned to receive these rays reflected from the first plane reflector and to reflect the same forwardly.

In witness whereof, I hereunto subscribe my name this 22nd day of December A. D., 1921.

REVELEY A. HALLETT.
